CONDITIONED AIR SUPPLY SYSTEM FOR TRAINS

David F. Zook, Evanston, Ill.

Application February 13, 1936, Serial No. 63,696

5 Claims. (Cl. 257—7)

The invention relates generally to air conditioning apparatus, and more particularly forced feed means of this character for use on railway trains.

5 An important object of the invention is to provide an air conditioned train wherein the entire air supply for the train is admitted at the upper forward end of the leading unit of the train so that under ordinary conditions of operation the 10 purity and cleanliness of the supply is insured and the cost of conditioning the air is reduced.

Another object is to provide an air conditioning system arranged for control exclusively by the engineer or operator who rides at the head end 15 of the train and is in a position to observe the condition of the air to be encountered as the train progresses.

Another object is to provide an air conditioned train wherein the air cleaning and conditioning devices are located in the power unit 20 or car, or closely adjacent thereto, and having in combination therewith a distributing system for delivering the conditioned air to the various units of the train, so that the mechanical elements of the air conditioning apparatus are 25 beyond the control of inexperienced trainmen or porters, and may be governed, inspected, or serviced at any time by the crew of the engine or power car.

30 Another object is to provide a new and improved air conditioning system for trains whereby duplication of air conditioning apparatus in each car is obviated so as to avoid excess weight, cost and complication of equipment.

35 Another object is to provide an air conditioning system for trains wherein recirculation of contaminated air is avoided and all air is taken in fresh from the exterior of the train.

40 Other objects and advantages will become apparent from the following description, taken in connection with the accompanying drawings in which:—

Figure 1 is a longitudinal central vertical sectional view of the power unit of a train embodying the invention;

Figure 2 is a front end view of the power car shown in Figure 1, the view being shown partially in section along the line 2—2 of Figure 1;

50 Figure 3 is a horizontal sectional view of the power unit taken substantially along the broken line 3—3 of Figure 1;

Figure 4 is a fragmentary longitudinal vertical sectional view of a tender or service car of the

train, which car normally follows directly behind the power unit shown in Figure 1;

Figure 5 is a transverse vertical sectional view of a passenger car taken along the line 5—5 of Figure 6;

Figure 6 is a fragmental horizontal view showing two adjacent coupled cars of the train with the roofs removed to show the air-ducts.

For purposes of disclosure the preferred form of the invention is illustrated in the drawings 10 and will hereinafter be described in detail as embodied in a particular type of train, but it is to be understood that this disclosure is not intended as a limitation of the invention to this type of train, it being contemplated that various 15 changes might be made by those skilled in the art to adapt the invention to other types of trains without departing from the spirit and scope of the invention as defined by the appended claims.

In the form chosen for disclosure herein, the invention is embodied in a train of the Diesel-powered type having a power unit or car 10, coupled at 11 to a second or tender car 12, and having a plurality of passenger cars 13 and 14 25 coupled behind the car 12 as shown in Figure 6. In accordance with the present invention, the train is provided with air conditioning means located principally in the power car 10 and having distributing means for delivering the conditioned air from the forward portion of the train to all of following passenger cars. The entire air supply to be conditioned is drawn in fresh from the exterior of the train so as to avoid reconditioning of contaminated air, and in the 30 present instance purity and cleanliness of the air supply is insured by admitting the entire supply through an inlet opening 15 extending throughout the entire width of the upper extremity of the forward end wall 16 of the power car 10. As 40 shown in Figures 1 and 3, the air enters through the inlet opening 15 into an intake chamber 17 from which it passes rearwardly of the car to the conditioning means.

In the form herein illustrated there is provided, as a part of the conditioning means, air cleaning means which is inter-related to the form and space requirements of the power car 10 in such a manner as to utilize efficiently the space 50 in the car, and this cleaning means is of such a character as to be readily cleaned or inspected at any time.

Thus, as shown in Figures 1, 2 and 3, the air cleaning means comprises a pair of elongated 55

passages or tubes 20 and 21 disposed longitudinally of the power car 10 adjacent to the ceiling thereof, and connected at their forward ends to opposite sides of the intake chamber 17 so as to receive air therefrom. The agency within the tubes 20 and 21 for cleaning the incoming air may take different forms, and in the present instance the tube 21 is provided with a spirally formed baffle member 22, inner surface of the tube 21 and the surfaces of the baffle 22 being preferably coated with an odorless oil or petroleum jelly to catch the dust particles which may enter with the air. In the other cleaning tube 20 an axially positioned spray pipe 23 is shown to which water from a supply tank 24 is forced through pipe 23 by a power driven pump 25. Return lines 26 from opposite ends of the tube 20 serve to drain the water back to the tank 24.

The cleaning tubes 20 and 21 are readily inspected, and the enclosed elements are readily removed for cleaning or repair by removal of end plates 27 (Figure 3) at the rear ends thereof. For the removal of the enclosed elements, aligned openings (not shown) in the rear end wall 28 of the power car are uncovered by removal of plates 28, which allows cleaner elements to be completely withdrawn from the power unit. The baffle type of cleaner shown in the tube 21 is of particular merit since it has no moving parts, and being of large volume, it requires cleaning only at infrequent intervals.

After being cleaned within the tubes 20 and 21, the air passes laterally from the rear portions of the tubes through short outlet pipes 30 into blowers 31, the blowers 31 being driven by a motor 32 so as to force the air through discharge pipes 33 into a heating unit 34 suspended from, but adjacent to, the ceiling of the car 10.

Heat for the heating unit 34 may be supplied from any desired source, but in view of the drive of the present train by tandem Diesel engines M-1 and M-2, the water from the cooling jacket of the rear motor M-2 is preferably utilized. Thus, heating unit 34 has vertical pipes 35 connecting upper and lower headers 36 and 37, and water from the top of the motor jacket is conducted to the upper header 36 by a valved pipe 38, and is returned from the lower header 37 to the lower portion of the motor jacket by a return pipe 39.

In the present embodiment additional heat is also imparted to the air at another point in its path by use of the jacket water from the forward motor M-1, and this end is preferably attained in such a manner that snow or sleet entering the inlet opening 15 is melted so as to prevent clogging of the air tubes 20 and 21, or clogging of a protective screen 40 which extends transversely across the intake chamber 17. Thus, as shown in Figures 1 and 3, a plurality of coils 41, between headers 41' and 41'' constituting a snow melter, are placed across the inlet opening 15 directly in the path of the incoming air, with supply and return pipe lines 42 and 43 connecting the headers 41' and 41'' in operative relation to the jacket of the forward motor M-1. Inspection and cleaning of the chamber 17 and screen 40 is permitted by a trap door 44 in the bottom of the chamber forwardly of the screen 40. The heating coils 41 supplied from the motor M-1, and the heating unit 34 supplied from the motor M-2 are in the nature of auxiliary radiators, and would be utilized only in cold weather. The motors M-1 and M-2 would be connected to con-

ventional radiators, not shown in the drawings, for the sake of clarity, and it will be noted that the outlet pipes 38 and 42 from the motors are valved so as to facilitate the use of such radiators. The pipes 38 and 42 are also provided with vertical pipe-stubs adjacent to the motor blocks, as shown, for use in making such connections to conventional radiators.

In order that the conditioning apparatus may be spared the undue cleansing load incident to short periods of operation of the train in zones of foul or unusually dusty air, such for example as during the passing of another train, or the passage through tunnels, the present apparatus provides for instant control by the engineer who is in a position to observe the conditions to be met. Thus, as shown in Figures 1 and 3, the two cleaning tubes 20 and 21 are provided with dampers 45 mounted at the forward ends of the tubes 20 and 21 on a common transverse shaft 46. From an arm 47 fixed to shaft 46 a rod 48 extends rearwardly to a pivoted connection on an operating lever 49 located within reach of the engineer. A short link 50 connected to the lever 49, acts when the dampers 45 are closed to open a switch 51 which acts to stop the blower motor 32, by cutting current in line 51'.

During such periods of closure of the dampers 45, the foul or dusty air which enters inlet 15 is by-passed or vented from the chamber 17 through openings 52 formed in the side walls 53 of the chamber. These vent openings 52 are closed during normal operation of the apparatus by valve members 54 carried on arms 55 fixed to the shaft 46. Operation of lever 49 performs the dual function of closing dampers and opening relief vents simultaneously.

In the present embodiment of the invention the air from the heater 34 passes to a cooling unit 56 located adjacent to the heater. As shown herein, the cooling unit 56 is mounted in the second or tender car 12 rather than in the power car 10, and the air is fed between the units 34 and 56 through a flexible connector pipe 57. The cooling unit 56 (Figure 4) comprises a cooling chamber 58 through which the air passes to a train pipe 59 extending rearwardly through the train. Within the chamber 58 is a heat exchange element 60 through which refrigerant is circulated from conventional mechanical refrigerating machine 61 mounted on the car floor beneath the chamber 58. Suitable thermostatic controls may, of course, be provided for the cooling unit in a conventional manner.

After being cooled and dehydrated in chamber 58, the air passes into the train pipe 59, which is preferably insulated as shown in Figures 4 and 5, and extends throughout the length of the train, there being suitable flexible connectors 62 between the cars, such as that illustrated in Figure 6. A cap (not shown) is employed at the rear end of the train pipe. To provide an ample flexing range in the connectors 62, the ends of the cars may be recessed as at 65, thereby permitting ample flexing of the connectors without too short bending. Preferably the train pipe 59 occupies a median longitudinal position immediately under the car roofs (Figure 5) and distribution of the conditioned air to the various parts of each car is obtained by the provision of auxiliary passages in the form of car pipes 66 which may be controlled to govern the distribution of conditioned air for each car. Thus, two longitudinally extending car pipes 66 are placed in each car, at

the level of the train pipe 59 and on opposite sides of the train pipe. The car pipes 66 have caps 67 at their ends and are connected to the train pipe 59 adjacent each end of the car by branch pipes 5 68. In each branch pipe 68 is a damper 69 pivoted on a generally vertical axis and adjustable by a lever 70 fixed to the damper shaft below the ceiling of the car.

From the car pipes 66 suitably spaced air ducts 10 71 extend laterally along the ceiling and downwardly along the sides of the car, suitable outlets 72 and 73 being provided in the ducts 71 as desired. Preferably the air ducts 71 are formed from structural channel members as shown in 15 Figure 6 so that the ducts serve as part of the car framing.

From the foregoing it will be apparent that the present invention provides an air conditioned train wherein the air supply is of maximum initial 20 purity by reason of its being obtained at the front of the train at the maximum distance above the track level; and that by reason of this construction the train is provided with pure air at a minimum cost for conditioning, even though excessive dust is raised due to operation of the train at the high speeds contemplated by recent 25 advances in the field of railroading.

Since the conditioning apparatus for the entire train is located in the power car, or closely adjacent thereto, the mechanical elements of the apparatus are afforded better care and servicing, and the operation of the apparatus is placed solely under the control of the engineer, who is best fitted, by training and location on the train, to 30 determine whether or not the apparatus should be in operation, and to adjust the air delivery to suit varying conditions.

Furthermore, a saving in weight and in lost car time is effected by locating the conditioning 40 apparatus in the power car and tender, and the form and positioning of the apparatus in the power car is such as to utilize the space efficiently and permit ready inspection and repair.

I claim as my invention:—

45 1. In an air conditioning system for trains having a plurality of cars and a power unit, means forming a single air intake for the entire train's air supply, said air intake being located at the head end of the power unit, a head end intake 50 chamber into which said intake discharges, a series of snow melter pipes in said air intake, means for heating said snow melter pipes, air outlet openings from said intake chamber, air cleaning devices fed from said openings, and a 55 fine mesh screen in said intake chamber interposed between said air intake and air outlet openings into said air cleaning devices.

2. In an air conditioning system for trains having a plurality of cars and a power unit, a single 60 air intake for the entire train's air supply, said air intake located at the head end of locomotive or power unit, a head end air intake chamber into which said intake discharges, a series of snow melter pipes in the path of the incoming air, said 65 intake chamber having an opening in its rear wall, an air cleaning device fed from said opening, said air cleaning device comprising an elongated chamber having a water spray pipe disposed longitudinally therein, a motor driven pump and supply 70 tank operatively connected to maintain a water jet spray from said pipe within said air cleaner duct or chamber, said device delivering air at its

rear end into a motor driven blower, heating and cooling units and a train pipe connected in series with said supercharger so that cleaned air is forced therethrough by said blower, said train pipe extending the full length of train and supplying conditioned air to each of the various cars in said train. 5

3. In an air conditioning system for trains having a plurality of cars and a power unit, a single air intake for the entire train's air supply, said air intake located at the head end of locomotive or power unit, a head end intake chamber fed by said intake, said intake chamber being provided with a fine mesh screen across said chamber, an opening in the rear wall of said chamber, an air cleaning device connected to receive air from said opening, said air cleaning device comprising an elongated duct, a multi-vane, spiral-type, air baffle screw mounted in said duct, the interior surfaces of said air cleaning device being coated with a non-odorous grease, a motor-driven blower to which said air cleaning device delivers air at its rear end, said blower being under the control of the engineer and operable to deliver a regulated supply of air to the 20 entire train. 25

4. In an air conditioning system for trains having a plurality of cars and a power unit, a single air intake for the entire train's air supply, said intake opening being located at the head end of power unit, a series of snow melter pipes positioned across said intake, a head end intake chamber into which said intake discharges, outlets in the rear wall of said intake chamber, air cleaning devices fed from said outlets, dampers in said outlets, means for opening and closing said dampers operable from engineer's seat in said power unit, motor driven blowers to which said air cleaning devices deliver air at their rear ends, said blowers being under the control of the engineer, 40 said control of blowers including a switch interconnected with said damper operating means operable to stop said blowers as an incident to the act of closing said dampers, and to start said blowers upon reopening of the dampers. 45

5. In an air conditioned system for trains having a plurality of inter-connected cars and a power unit, a single air intake for the entire train's air supply, said air intake being located at the head end of the power unit, said air intake admitting air to a head end intake chamber, a series of snow melter pipes in said intake opening, means for heating said snow melter pipes, openings in the rear wall of said intake chamber, air cleaning devices fed from said openings, motor driven blowers into which said air cleaning devices deliver air from their rear ends, a heating unit into which said blowers force air under pressure, means for heating said heating unit, an outlet from said heating unit, a cooling chamber connected to 50 receive air from said outlet, an insulated train pipe receiving air from said cooling chamber, said train pipe extending the full length of train and having flexible connecting hose between adjoining car ends, car pipes in each car formed to said 55 train pipe by short connector tubes, air control valves in each of said connector tubes, and a system of air ducts connected to said car pipes for final distribution of conditioned air throughout each of said cars. 60 65 70
